UNITED STATES PATENT OFFICE.

JOHN DELLINGER, OF BUFFALO, NEW YORK.

TOY.

Application filed May 17, 1924. Serial No. 714,176.

My invention relates to improvements in toys.

The primary object of my invention is the production of a convertible toy, including a doll swing, a table, a blackboard or slate, and a drying rack for dolls' clothes, convertible one into another.

Another object of my invention is to provide a toy of this kind in which parts thereof can be folded into a small space and other parts thereof be assembled or disassembled to convert the toy from one kind to another.

A further object of my invention is to provide a toy comprising a plurality of parts, one of which is foldable to serve as a frame for supporting a table-top, convertible into a black board or slate, also supported by said frame, and to support a doll swing, as well as serving as a clothes rack for dolls' clothing and the like.

A still further object is the production of an attractive toy especially designed for young girls and which, in addition to serving as an article of pleasure will also furnish educational advantages.

With the above and other objects in view, the invention consists in the novel features of construction and in the arrangement and combination of parts to be hereinafter described and more particularly pointed out in the subjoined claims.

In the drawings:—

Fig. 1 is a perspective view of the toy converted into a doll swing.

Fig. 2 is a perspective view of the same converted into a clothes-rack for supporting dolls' clothing and the like.

Fig. 3 is a side elevation of the device showing the same converted into a table.

Fig. 4 is a side elevation of the device showing the same converted into an educational toy having a small blackboard or slate supported in a position to permit a child to conveniently draw, figure, or write thereon.

Fig. 5 is a perspective view of the frame in folded condition.

Fig. 6 is an enlarged fragmentary vertical section of the device in folded condition, the section being taken through two opposite legs of the frame and through the spreader used for opening or closing the frame and retaining the same in either open or closed position.

Fig. 7 is a detached perspective view of one of the table-top supporting rails.

Fig. 8 is a detached perspective view of

the swing used in conjunction with the frame.

Fig. 9 is a horizontal section through the frame taken in a plane directly above the spreader and showing said spreader expanded to cause the frame to assume an open position.

Fig. 10 is a detached perspective view of the center member of said spreader.

Fig. 11 is a detached perspective view of one of the four links used in the construction of said spreader.

Fig. 12 is a horizontal section taken on line 12—12, Fig. 3.

Fig. 13 is a sectional perspective view of the combined table top and slate or black-board.

Fig. 14 is a fragmentary vertical section taken on line 14—14, Fig. 9.

Fig. 15 is an enlarged transverse section taken on line 15—15, Fig. 5.

Fig. 16 is a detached perspective view of the wash-board retainer.

Referring to the drawings in detail, the reference numeral 17 designates a foldable frame, which comprises four legs 18 connected together at their upper ends by a loop 19. A short distance below loop 19 said legs 18 are connected together by a spreader 20. In preferred form each of the legs is constructed of a strip of tin or other like material having opposite longitudinal marginal portions rebent and extended inwardly on the inner side of the leg, as at 21, to form longitudinal grooves 22, the edges of the material being spaced apart, as shown at 23. The rebending of the marginal portions serves to stiffen the legs so that they will withstand considerable strain without bending, and it also permits the attachment to the leg of certain other parts, to be hereinafter set forth.

The loop 19 is substantially rectangular so as to form four sides, and the upper ends of the legs are curved around the four sides of the loop so that a hinged connection is provided for the legs and at the same time the legs are connected together by said loop so that they may be swung outwardly to assume a spread condition.

In order that the tin or other material used in the construction of the legs does not come in contact with the surface on which the toy is placed and thus mar the same, I have provided elongated wire feet 24 at their lower ends which have rounded lower

- contacting ends, the said feet being of elongated U-formation and having their side members fitted into the grooves 22 formed by rebending the longitudinal marginal portions of the tin or other material, the lower ends of these rebent portions being firmly pressed around said side members, as at 25, to securely fasten said wire feet to the legs, as best shown in Fig. 15.
- 10 The spreader 20 comprises a substantially rectangular plate or center member 26 formed of tin or other suitable material, and having at each of its four sides an upwardly and inwardly curved portion or loop 27, each of which is adapted to receive the inner cross member of an elongated loop-like wire link 28, said curved portions or loops 27 retaining the links 28 thereon and permitting said links to swing from horizontal to substantially vertical position.
- 15 Each of the links 28 is formed of a short length of wire, and the ends 29 of such wire are bent inwardly from the side members of the link, with a space 30 between said ends.
- 20 The ends 29 of the links are inserted into the legs 18 from opposite edges thereof and terminate within the grooves 22 of said legs, serving as the outer pivots for said links, suitable openings being formed in said legs for such purpose, while the inner transverse member of said links serve as the inner pivots. In this manner the four legs are connected together at points a short distance from the upper ends thereof and the spreader formed by the plate or center member 26 and links 28 is either expanded, as shown in Figs. 1, 2, 3, 4, 9 and 14, or collapsed as shown in Figs. 5 and 6. When expanded, both the plate or center member 26 of the spreader and the links 28 lie in a substantially horizontal plane and are so retained by reason of the legs or, more particularly, the feet at the lower ends of the legs having frictional contact with the table or other support on which the toy is placed. In fact, when the spreader is in perfectly horizontal position, the links are in what may be termed a "dead-center" position, and considerable pressure inwardly on the legs 50 would be required to cause the parts of the spreader to assume any other position. It is, however, a simple matter to cause the spreader to collapse, as it is only necessary to place the finger against the top of the plate or center member 26 and press downwardly, whereupon the legs will be drawn inwardly and the frame caused to be folded.
- 55 Fastened to the inner side of one of the legs is a string or cord holder 31. This string or cord holder is formed of a piece of wire bent, as best shown in Fig. 16, so as to form a comparatively wide intermediate portion 32, and to offset narrower portions 33 serving as hooks. The wide intermediate portion 32 is placed against the inner side of

one of the legs, with the opposite side parts thereof within the grooves 22 of the leg, and the incurved marginal portions of said leg overlying said opposite parts are pressed inwardly in firm contact with said side parts 70 to clamp the holder firmly to the leg. The hooks 33 extend upwardly and downwardly, respectively, from said leg so as to form oppositely-disposed hooks on the leg, which are 75 spaced apart.

Each of the legs has a number of outwardly extending projections 34 fastened or formed thereon; but preferably these projections are in the form of headed knobs fastened through the metal forming the legs 80 in the same manner as an ordinary rivet. A string or cord 35 has one end fastened to the lowermost knob of the leg to which the string or cord holder 31 is applied, and this string or cord is directed inwardly around the leg and thence wound or looped around the opposite knobs of the holder 31, as shown in Fig. 1. When it is desired to convert the device into a clothes rack, the cord is unwound from the holder 31 and passed 90 around the frame. For this purpose the knobs 34 of the legs are arranged in three horizontal sets so that the string or cord is arranged to provide stretches which completely surround the frame, and are arranged one above another, as clearly shown in Fig. 2. The string or cord is first wound around the frame and twisted around the knobs of the lowermost set. It is then directed upwardly along one of the legs to one 95 of the knobs of the next higher set where it is continued around the frame and thence again directed upwardly to one of the knobs of the uppermost set, where it is again continued around the frame. To these different stretches of string or cord, dolls' clothing or other small articles may be fastened, as clearly shown by dotted lines in Fig. 2. The string or cord when not in use can be easily unstrung from the frame and 100 looped around the opposite knobs of the holder 31, where it will be out of the way when using the device for other purposes.

Each of the legs has an opening 36 formed therein, these openings being in the same 115 horizontal plane, and the openings of adjacent legs are used in pairs. Through each pair of these openings a supporting rail 37 may be placed. Each of these rails is formed of a strip of tin or other suitable 120 material and has its longitudinal marginal portions rebent upon itself, as at 38, to stiffen the rail so that it will properly support a table-top, to be hereinafter described, and will not easily bend. One end of each rail 125 is bent upon itself, as at 39, so as to eliminate all sharp edges and thus guard against injury to a child when playing with the device. At the other end of the rail a transversely elongated handle 40 is formed which 130

is constructed of a short length of wire bent into loop form and having the ends thereof inserted underneath the rebent portions 38 of the rail, as at 41, the rebent portions of the rail being firmly pressed around the ends of the wire so as to securely fasten the handle to the rail. The handles of the rails, by reason of being extended laterally, serve also as stops. A rail may be inserted through each pair of openings 36, so as to project with opposite ends from adjacent legs. These rails are therefore disposed in parallel relation and resting upon the same is a combined table-top and blackboard or slate, designated by the numeral 42. This table-top is positioned between the legs, as clearly shown in Figs. 3 and 12, and while it may be constructed of any suitable material, I preferably form the same of a sheet of tin, or other like material, and rebend the marginal portions thereof, as at 43, thus eliminating all sharp edges and strengthening the table top so that it will not easily bend. The under side of this table top, or slab as it may be referred to, is coated with a paint or other substance so as to convert the surface into a blackboard or slate on which chalk or slate pencil may be used, and designs or pictures drawn, or it may be used for figuring and writing thereon. The device therefore is an educational device, as well as a toy.

When using this slab as a blackboard or slate, it is set onto the projecting ends of the rails 37 having the handles 40, as shown in full lines in Fig. 4, and in dotted lines in Fig. 3, the slab having its lower edge in contact with the upper edges of said rails and reclining against two of the legs of the frame. One of the laterally-projecting portions of each handle serves as a stop for the slab when for any reason the latter tends to slide along the rails; or, if desired, the rails may be thrust through the legs of the frame to a greater extent than shown in Fig. 3, so that the upwardly-projecting portions of the handles 40 will be in contact with the lower marginal portion of the slab. In Fig. 3, however, I have shown the slab as a table top in which case it is immaterial whether or not the handles of the rails are in close relation to the frame so long as the rails receive proper support at each end, and I have merely utilized this figure to illustrate the position of the slab when used as a slate or blackboard. Preferably, however, the handles are in contact with the slate or blackboard so that the latter cannot slip from its position.

In order to provide a compact device I have arranged to place the rails 37 into the frame when the device is not in use, so that they do not become readily mislaid and so that they will utilize the space between the legs when the frame is folded. For this

purpose the plate or center member 26 of the spreader has an opening 44, and when the device is folded the rails are thrust through the loop 19 at the top of the frame, and thence through the opening 44 in said spreader, and extended downwardly until the opposite laterally extending portions of the handles 40 rest against the hinged upper ends of opposite legs, as clearly shown in Fig. 5. The rails are therefore conveniently stored within the frame, when folded.

I also provide a doll swing which comprises a hanger 45, two strings or cords 46 fastened to said hanger, and a seat 47 suspended by said strings or cords. The hanger is formed of a short length of wire bent at equal distances from a point centrally between its ends to form a straight transverse medial member 48 and open loops 49, at opposite ends of said medial member to which the strings or cords 46 are secured. From these open loops the wire is directed upwardly and inwardly, as at 50, and thence parallel with the medial member 48 between the open loops 49, as at 51, the ends of the wire being spaced apart, as at 52.

The end portions 51 of this hanger are hung over the plate or center member 26 of the spreader, as clearly shown in Fig. 1, each of said end portions being positioned between two loops 27 of said plate or center member 26, said loops serving as stops and preventing accidental displacement of the hanger.

The seat 47 is constructed of an elongated piece of material 53, preferably of tin, and a frame 54 formed of wire. The elongated piece of material 53 is bent or creased to form a seat portion 55, and a back rest 56. The wire forming the frame is bent or otherwise fashioned to form a rear cross member 57 around which the upper end of the back rest is curved or to which it is otherwise secured, two side members 58 directed downwardly from opposite ends of the rear cross member 57 to the front end of the seat portion 55, the wire being thence bent inwardly, as at 59 from opposite side members, and around said inwardly bent portions the front end of the seat portion 55 is curved, or otherwise fastened. Said seat portion has a slot or opening 60 formed in its front end, and one of said inwardly bent portions 59 terminates at said slot while the other end thereof is extended through said slot and directed upwardly and rearwardly, as at 61, thence downwardly, as at 62, and has the lower end thereof recurved, as at 63, to form an eye which is in close proximity to or may be in contact with the seat portion 55.

The parts 61 and 62 serve as a retainer device adapted to project upwardly between the legs of a doll 64 seated on the swing, as shown in Fig. 1. The side rails are pro-

vided with upwardly-extending arms 65 offset with respect to the two side members 58, as at 66.

When positioning the doll on the swing, the arms of the doll are placed over the side members of the seat and the upwardly-extending arms 65 bear against the shoulder of the doll. Therefore, with the retainer device extending upwardly from the seat portion of the swing and positioned between the legs of the doll, and the arms of the doll placed in rear of the retainer arms 65, the doll will be retained on the swing without possibility of its sliding from the seat.

Having thus described my invention, what I claim is:

1. A foldable toy comprising a frame having a plurality of legs pivotally connected at their upper ends to swing toward and from each other, and slab-supporting rails supported by adjacent legs and spanning the space between the same when said frame is unfolded, said rails being adapted to be inserted between said legs through the upper end of said frame when folded.

2. A toy comprising a frame having four legs and means including horizontal pivot elements in the form of a loop for connecting said legs together at their upper ends, a collapsible spreader pivotally connected to said legs near their upper ends, and a swing suspended from said spreader.

3. A toy comprising a frame formed of a plurality of legs, a rectangular loop to which the upper ends of said legs are connected, and a spreader comprising a center member and loop-like wire links pivotally connected at their inner ends to said center member and at their outer ends to said legs.

4. A toy comprising a frame formed of a plurality of legs, each leg being formed of a strip of sheet metal having its longitudinal marginal portions rebent and the edges of said rebent portions spaced apart, each leg having alined openings in opposite edges, a wire loop connecting the upper ends of said legs to permit the latter to swing outwardly, and a spreader having a rectangular member provided with loops at its sides and elongated wire links whose inner ends are rotatable in said loops and whose outer ends are formed by the terminals of the wire from which they are constructed, the terminals of each link being inserted into the alined openings of a leg.

5. A toy having a frame formed of a plurality of legs pivotally connected at their upper ends and having their longitudinal marginal portions rebent inwardly to form grooves and having their edges spaced apart, and a foot for each leg formed of wire fashioned into U-formation with its side members fitted into the grooves of said legs and the rebent portions of said legs curled around said members.

6. A toy having a frame formed of a plurality of legs pivotally connected together at their upper ends and having said upper ends spaced apart to form an opening between the same, each of said legs having an opening near its lower end, and supporting rails, each rail adapted to be inserted through the openings of two of said legs when said legs are spread, each supporting rail having a transversely elongated part at one end and said rails being adapted to be inserted through the opening between the pivoted upper ends of said legs when the frame is collapsed with the transversely elongated portions thereof resting against the upper ends of opposite legs.

7. A toy comprising a frame having spaced legs, a pair of parallel rails applied to said legs when spread apart, and a slab serving as a table adapted to lie flat upon and be supported by said rails between said legs.

8. A toy comprising a frame having legs pivotally connected together at their upper ends to permit of their being spread apart, means for retaining said legs in spread condition, said legs having horizontally alined openings therethrough, rails inserted through said openings and projecting outwardly from at least two of said legs, and a slab set edgewise on the projecting portions of said rails and inclined against said legs, said rails being also adapted to support said slab between said legs in flat condition.

9. A toy comprising a frame having four legs, a rectangular loop connecting the upper ends of said legs together, said legs having horizontally alined openings therethrough, rails passing through said openings in parallel relation and having transversely elongated portions at one end thereof, a writing slab set edgewise on said rails and inclined against the transversely elongated portions of said rails, said slab being also adapted to be placed flatwise on said rails between said legs and serve as a table.

10. A toy comprising a frame having four legs, a rectangular loop to which the upper ends of said legs are pivotally connected, said legs having horizontally-alined openings therethrough, rails passed through said openings in parallel relation when said legs are spread and projecting at opposite ends, each of said rails having a transversely elongated loop at one end, said rails being inserted through the rectangular loop at the top of the frame when the legs thereof are folded and having the transversely elongated portions thereof bearing against the upper ends of opposite legs.

11. A toy comprising a foldable frame having four legs, a rectangular wire loop to which the upper ends of said legs are pivotally connected, each of said legs having an opening between its ends with the openings of all legs in horizontal alinement and adapt-

ed for use in pairs, a supporting rail passed through each pair of said openings when said legs are spread and projecting at opposite ends, each rail having a transversely elongated wire loop at one end, said rails being adapted to be inserted through said rectangular loop when said frame is folded with the transversely elongated wire loops thereof resting against the upper ends of opposite legs.

12. A toy comprising a foldable frame having four legs, a rectangular wire loop to which the upper ends of said legs are pivotally attached, a spreader connecting said legs near their upper ends, said spreader comprising a center member having a central opening and four loops and wire links pivotally connected to said loops at their inner ends and having pivotal connection at their outer ends with said legs, rails supported by said legs between their ends when the legs of said frame are spread, each rail having a transversely elongated loop at one end and being adapted to be inserted through said rectangular loop and through the opening in the center member of said spreader with the opposite end portions of said transversely elongated loops bearing against the upper ends of opposite legs.

13. A toy comprising a frame having legs pivotally connected together at their upper ends and having openings therethrough arranged in pairs, a rail extending through each pair of openings, and a slab adapted to be set on edge and rest upon said rails with its inner side in contact with two of the legs of said frame, said slab having one side thereof in contact with two of the legs of said frame and having its other side thereof fully exposed.

14. A toy comprising a frame having a plurality of legs pivotally connected at their upper ends and having a spreader near its upper end comprising a center member and

a plurality of open wire links pivotally connected to said legs, a swing having a hanger supported from said center member, cords attached to said hanger, and a seat attached to the lower ends of said cords.

15. A toy comprising a frame having a plurality of legs pivotally connected together at their upper ends, a spreader comprising a center member and open wire links having their inner ends pivotally connected to said center member and their outer ends pivotally connected to said legs, a swing having a hanger formed of wire and fashioned to provide a horizontal medial portion, open loops at opposite ends of said medial portion, upwardly and inwardly-directed members extending from the loops and inwardly-directed terminals adapted to rest upon said center member between adjacent links, cords secured to the open loops of said hanger, and a seat secured to the lower ends of said cords.

16. A toy comprising a frame having legs pivotally connected together at their upper ends, a swing supported from said frame near its upper end and having a seat formed of wire bent to provide a rear cross member, side members extending forwardly from said rear cross member and provided with upwardly extending retainer arms between their ends, and a front cross member formed by bending the wire inwardly from opposite side members, one of said inwardly bent portions being continued upwardly and rearwardly and thence downwardly, and strip material bent or creased between its ends to form a back rest for said seat and a seat portion, the upper end of said back rest being secured to said rear cross member and the front end of said seat portion being secured to said front cross member.

In testimony whereof I affix my signature.

JOHN DELLINGER.
